ESCAPE MEANS FOR A SUBMARINE WHEN SUBMERGED

Filed Jan. 31, 1930

UNITED STATES PATENT OFFICE

JOHN M. CLARK, OF NEW YORK, N. Y.

ESCAPE MEANS FOR A SUBMARINE WHEN SUBMERGED

Application filed January 31, 1930. Serial No. 424,750.

The device, the subject of this invention, is intended as a means for providing egress or escape from a submarine when the submarine is submerged and particularly at such time as when it is found that through failure of the machinery or otherwise the submarine cannot again reach the surface.

I am aware that other suggestions of this nature have been made but in this invention it has been my object to construct a device simple of operation and while efficient, yet so small that it will not take an amount of space required for other devices and such as are common to a submarine and necessary for the functioning of the submarine as such.

A number of these escape means may be provided but I would suggest that they be arranged one forward and one aft and if room is found, and it is otherwise found convenient, that one be established at approximately the midship section.

Another object of the invention is to provide means which will make it possible for the men in the submarine to assist in the discharge of each successive man and then to make it possible for the last man to leave the submarine.

Another object is to provide a device of this type which may be employed again and again and for that reason I provide for the utilization of an outside lifting force; in other words the device itself, is not buoyant and is of added negative buoyancy when supporting the weight of a man of ordinary size.

Another object of the invention is to provide necessary auxiliaries such as an interior signalling system, oxygen tanks and lime containers so that life may be supported within the device for the longest possible period of time. The means for carrying out the foregoing objects and others not particularly previously referred to, together with the details of construction, will be found in the specification which follows, and the accompanying drawing should be referred to for a complete understanding of the specification.

In the drawing:—

Figure 1 is an assembly view of my device partly in section, a part of a submarine being shown.

Figure 2 is an enlarged sectional view of the container.

Figure 3 is a sectional view taken on about the line 3 of Figure 2 and viewed in the direction of the arrow.

Figure 4 is a view on the line 4—4 of Figure 2 and viewed in the direction of the arrow.

Figure 5 is a top plan view, and

Figure 6 is a side elevation of a part removed.

Similar reference numerals indicate like parts in all the figures where they appear.

The portion of the submarine shown is indicated at 1. The submarine may be of any desired shape or size and the bulkheads 2 and 3 may or may not be decks. The upper bulkhead 2 will probably be a deck. The lower bulkhead 3 will probably indicate a twin deck enclosing chamber for a valve 4 which is an exaggerated gate valve in that this valve is constructed with a sliding member, but room must be provided in the extension 5 so that the slide can be fully withdrawn to allow a clear passage through this valve. The valve will of course be secured by regular flanges and gaskets, as suggested at 6, if such are required. In the space between bulkheads 2 and 3 I arrange another valve as shown at 7. This is a flooding valve and will be referred to later.

Secured to the under side of the bulkhead 3 and through the medium of gaskets 8 if such is found desirable, is a cylindrical member 9. Into the side of this cylindrical member I introduce a flooding valve 10. At the bottom of the cylindrical member is a valve 11 similar in all respects to the valve 5 and having an extension 12 for the reception of the valve disc. I may or may not provide a ladder 13 under the cylindrical member 9 for a purpose that will appear obvious as the specification progresses.

It will be noted that there is a passage 14 through the bulkhead 2 and a passage 15 through the bulkhead 3.

Normally arranged within the cylindrical member 9 is the escape cylinder 16 having an eye block 17 and guide handles 18 secured

at the upper end thereof. This escape cylinder is best seen in Figure 2.

The escape cylinder 16 is provided with a head 19 which supports eye block 17 and the handles 18 which may be formed integrally therewith. Through the head 19 I arrange bull's eyes 20 and 21 which may be provided with lenses but which of course must be water tight. On the inner side of the head 19 will be noted a reflector 22 to reflect the light from the lamp 23 recessed in the head 19. A battery for this lamp may also be arranged in the recess 24 wherein the lamp is contained.

Secured to the inner side of the head 19 are lugs 25 and 26, each supporting a tension hook, the hooks being shown at 27 and 28. These hooks are adapted to receive chains 29—30 which will be later referred to. The head 19 may be screw-threaded to the escape cylinder 16 or otherwise secured thereto. Ordinarily it will never be found desirable to remove this head 19. Within the cylinder 16 I arrange two ladders or two series of hand-hold members as shown at 31 and 32, these hand-hold members being arranged at opposite sides of the cylinder. Within the cylinder is an oxygen tank 33 and a lime container 34 for emergency use, the lime container being intended to contain a quantity 30 of a lime derivative which absorbs the carbon monoxide exhaled in breathing by the person within the cylinder 16.

The chains 29 and 30 are provided with turn buckles as shown at 35 and 36, and the lower ends of these chains are engaged in lugs 37, 38, the lugs being secured to the enclosure plate 39 for the cylinder 16. This plate 39 may be removed at will and will be removed for the entry of a person into the cylinder 16. Ordinarily the plate or disc 39 will be retained in position by a bar 40 operating on lugs 41 and 42 found in the cylinder walls. The bar may be rotated and later secured by means of a hand wheel 43 exterior 45 of the plate or disc 39.

The disc 39 will be placed in position and secured by means exterior of the cylinder 16 under ordinary conditions. That is, when a man is to leave the submarine by means of the cylinder 16, the other men in the submarine will secure the disc 39 in position. But when the last man is to leave the submarine he will first draw up the plate, kick over the clamping bar 40 as far as possible, and then by 55 means of the lever hooks 27 and 28 draw up on the chains 29 and 30, thus securing the disc in a water tight association with the cylinder 16. The details of the hooks 27 and 28 are shown in Figure 6.

60 In the operation of my device, communication having been established, a diver is lowered to the deck of the sunken submarine. A man then enters the cylinder 16, the disc is placed in position, the valve 12 closed, and thereupon a diver opening the by-pass 44

will equalize this pressure on the valve 4, whereupon this valve will be opened and the diver will engage a hook into the eye-block 17 and thereafter the cylinder 16, and its occupant is raised to the surface, the disc 39 70 removed, and the occupant leaves the cylinder.

The cylinder may be employed again and again, the disc 39 being replaced for each lowering, and when the cylinder 16 is within 75 the casing 9 and the valve 4 closed, the bleeder valve 10 is opened to allow the water in the casing 9 to escape and to make it possible to open the valve 11.

When the last man is in the escape cylinder 80 16 the valve 11 cannot be closed. Therefore, because of the additional pressure on the exterior of the submarine, it will probably be found impossible to withdraw the escape cylinder 16. Under such conditions the 85 diver opens the equalizing valve 7 allowing water to enter the chamber of the submarine and the pressure therein to become equalized with the exterior pressure and thereafter the escape cylinder 16 can be withdrawn without 90 difficulty.

For the purposes of controlled signalling with the exterior the mirrors 22 may be hinged so that they can be moved back and forth to change the intensity of the light reflected from the lamp 23. The size of all of the parts or the peculiar construction thereof may be changed to accomplish desired purposes and other modifications may be made within the scope of the appended claims without departing from the principle or sacrificing the advantages of the invention. 95

Having carefully and fully described my invention, what I claim and what I desire to secure by Letters Patent is:—

1. An escape means for a submarine comprising a cylindrical casing, a cylinder contained therein means for sealing said cylinder from the interior or exterior thereof, one said means comprising a plurality of chains having lever operated hooks therein for securing certain parts of each said chain. 110

2. In a device of the character described, the combination with a submarine of a valve pocket, a plurality of valves in said pocket and shielded thereby, a casing secured at the inner side thereof, a normally closed casing within said first mentioned casing, a plurality of means for closing said normally closed casing, one of which is a quick operating adjustable means, and means for securing a hoisting means to said normally closed casing. 115 120
